Attorney.

UNITED STATES PATENT OFFICE

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS

CORNER-BAR CONSTRUCTION FOR STORE FRONTS AND THE LIKE

Application filed June 2, 1928. Serial No. 282,331.

This invention relates to a corner bar construction, which is particularly adapted to be used between adjacent edges of plate glass windows as used in store fronts or similar structures.

The object of the invention is to provide a bar for this purpose, having practical and convenient means for anchoring the same at the top and bottom and so arranged that the glass-supporting rail may be secured thereto so as to face in any direction desired. Thus, a single standard construction may be used either for an outside or inside corner, whatever its angle may be, or it may be used for a division bar between two glass plates disposed in the same plane.

The nature of the invention and the manner in which it may be used will be more particularly explained in connection with the accompanying drawings, which illustrate the same in detail.

In the drawings:—

Figure 1 is a partial front elevation of the invention as used in store front construction. Fig. 2 is a vertical section of the same taken centrally of the division bar.

Fig. 3 is a horizontal section of the same.

Fig. 4 is a detail plan view of the base cap.

Fig. 5 is a detail plan view of one of the anchors.

Fig. 6 is a view, partly in elevation and partly in section, of the anchor shown in Fig. 5.

Fig. 7 is a horizontal sectional view of the invention as embodied in a division bar.

Fig. 8 is a view similar to Fig. 7, illustrating a reverse corner bar.

The invention, as illustrated herein, is preferably of extruded bronze construction. It is shown, in Figs. 1 and 2, in connection with an opening, the upper and lower edges of which are indicated at 10 and 11 respectively. In the preferred construction, the column 12 is hollow and substantially cylindrical in shape and its convex surface may be fluted. It is made in two sections, one of which has internal overlapping flanges 13 secured to the other section by machine screws 14 or the like. Each end of the column is mounted upon an anchor 15, which has a reduced end

portion 16 fitting within the end of the column. The anchor is substantially cylindrical, with a transverse web 17, which is secured by suitable screws 18 to the top or bottom edge of the opening, as the case may be. The reduced portion 16 of the anchor is formed with notches 19 for receiving the ends of the respective flanges 13. 55

The column 12 constitutes a support, on which the glass-supporting rails 20 are secured. Each of these rails is formed with a concave cylindrical face adapted to fit against the surface of the column, to which it may be secured by screws 21. By tapping suitable holes in the column, the rails 20 may be secured in any relative positions desired. Each rail 20 has an outer flat face, to which moldings 22 of any suitable construction may be secured for receiving and supporting the edge of the glass plate 23. 70

The side edges of the rails 20 are beveled to form faces which are disposed in radial planes, so that when the construction is used for a right angle corner, as shown in Figs. 1, 2 and 3, the adjacent edges of the rails fit 75 against each other, and the upper and lower ends of the column 12 are finished by head and base caps 24 and 25 respectively, which are secured to the respective anchors 17 by suitable screws 26. As shown in Fig. 3, the 80 cap extends for slightly more than a semi-circumference and fits against the opposite beveled edges of the rails 20.

When the invention is used for a division bar, as shown in Fig. 7, the same construction is used, except that two oppositely disposed cap segments 27 and 28 are used instead of the single segment 25. 85

In the reverse angle bar, as shown in Fig. 8, the same construction is used, with the exception that the cap segments 29 and 30 are of suitable length to correspond to the desired angle. 90

From the foregoing description, it will be understood that the corner or division bar may be very easily installed by first securing the anchors 17 in position, with the respective caps 24 and 25 secured thereto. The two sections of the column 12 are then placed in position, with the ends of the flanges 13 fit- 100

ting within the notches 19, and the two sections are then secured together by inserting the screws 14. The rails 20 are then placed in the position desired. Thus, a uniform standard construction may be used for all 5 corner and division bars, the relative positions of the two rails 20 depending upon the lengths of the respective cap segments 24, 25, 27, 28, 29 and 30.

10 The rails 20 are adapted to receive any type or style of glass securing means which it may be desired to use. The style and construction of the various corner or division bar elements may also be modified considerably 15 without departing from the scope of the invention as claimed.

What I claim is:

1. In a construction of the class described, 20 a hollow substantially cylindrical column, anchors secured in abutting relation to the ends of said column and having reduced portions extending beyond the abutting surfaces and fitting into the ends of the column to prevent lateral displacement of the same, said column being in two sections, one of said sections 25 having internal flanges lapping the interior face of the other section and secured thereto, said reduced portions of the anchors having recesses into which the end portions 30 of said flanges fit, and rails secured to said column for mounting glass holding members.

2. In a construction of the class described, 25 a hollow substantially cylindrical column, anchors fitting the respective ends of the column to support the same, said column being in two sections, one of said sections having internal flanges lapping the interior face of the other section and secured thereto, said anchors having recesses into which the end 35 portions of said flanges fit.

3. In a construction of the class described, 40 a hollow substantially cylindrical column, anchors fitting the respective ends of the column to support the same, a pair of rails each having a concave face fitting against said column and an opposite face to which glass holding members may be secured, means for securing said rails to the column to form a division bar or a corner bar with any desired 45 angle, said rails also having side edges beveled to planes substantially radial with respect to said column, and arcuate base and head caps fitting against the ends of said column, with the ends of said caps fitting against 50 said beveled edges.

In testimony whereof, I have hereunto signed my name to this specification.

CHARLES G. NELSON.
